UNITED STATES PATENT OFFICE.

CUSHING C. HARLOW, OF BROCKTON, ASSIGNOR, BY MESNE ASSIGNMENTS,
TO EDWIN G. CARLETON, OF CHELSEA, MASSACHUSETTS.

KEY-FASTENER.

SPECIFICATION forming part of Letters Patent No. 393,302, dated November 20, 1888.

Application filed February 14, 1888. Serial No. 264,012. (No model.)

To all whom it may concern:

Be it known that I, CUSHING C. HARLOW, a citizen of the United States, residing at Brockton, in the county of Plymouth and State of Massachusetts, have invented certain new and useful Improvements in Key-Fasteners; and I do hereby declare that the following is a full, clear, and exact description of the invention, which will enable others skilled in the art to which it appertains to make and use the same.

This invention relates to key-fasteners; and its object is to provide an improved device of this class possessing merit in point of simplicity, durability, inexpensiveness, and general efficiency.

In the drawings, Figure 1 is a perspective view showing my invention applied to a door. Fig. 2 is a longitudinal sectional view. Fig. 3 is a transverse sectional view.

Corresponding parts in the figures are denoted by the same letters of reference.

Referring to the drawings, A designates a plate, preferably circular in shape and provided with two or more perforations, a, for the reception of screws or fastening devices to secure it to the door. Upon the face of this plate is provided a forwardly-projecting centrally-arranged arm, B, slotted longitudinally and centrally, as shown at b.

Within the slot b is pivoted the end of a chain, C, preferably constructed of flat metallic plates c, every other link of said chain being a single plate, while the intermediate links are composed of two plates pivoted at their corresponding ends, one at each side, to the adjoining end of the single-plate link. It will be observed that the link pivoted in the slotted arm is of a single plate, while the link at the other end of the chain is of the double-plate construction above described.

At the outer end of the chain, between the plates forming the link, are pivoted the ends d d of two flat spring-arms, D D, which together are of an approximately V shape. Near the outer ends of these spring-arms they are bent inwardly at an angle to the main portion, as shown at d', thence on a line with said main portion, as shown at d'', and the extreme ends are bent or turned outwardly at an angle (see d'') to the portion d', thereby forming an approximately rectangular recess, D', for the purpose hereinafter set forth.

The operation and advantages of my invention will be readily understood by those skilled in the art to which it appertains. The plate is secured to the door in such a manner as to allow vertical movement or adjustment of the chain and spring, and at a point below the key equal to the length of the device.

To secure the key in the lock, the eye at the outer end is turned to a horizontal position and the ends of the spring-arm inserted therein, the sides of said eye engaging the recesses at the outer ends of the spring-arms.

I claim as my invention—

The combination, with the plate A, having a slotted arm, B, of the flat link-chain C, having two plates on its outer end, and the spring-arms secured between said end plates and diverging outwardly in opposite directions, their upper ends being bent to form recesses, as D, for the reception of the key, substantially as described.

In testimony whereof I affix my signature in presence of two witnesses.

CUSHING C. HARLOW.
